UNITED STATES PATENT OFFICE.

JOHN F. STEWARD, OF CHICAGO, ILLINOIS.

MOWING-MACHINE.

SPECIFICATION forming part of Letters Patent No. 678,059, dated July 9, 1901.

Application filed February 2, 1899. Serial No. 704,259. (No model.)

To all whom it may concern:

Be it known that I, JOHN F. STEWARD, a citizen of the United States, residing in Chicago, in the county of Cook and State of Illinois, 5 have invented certain new and useful Improvements in Mowing-Machines; and I do hereby declare the following to be a full, clear, and exact description of the invention, such as will enable others skilled in the art to which it appertains to make and use the same.

The present invention relates to a well-known type of mowing-machine, and more especially to those parts of the machine which form the subject of the prior patent granted 15 to me February 4, 1896, No. 554,010. In respect of this patent the present improvements have been designed with a view to enabling the driver to throw the cutter crank-shaft into and out of gear with the counter-shaft by means of his foot without leaving his seat and without having to stoop over and reach down to the position where the clutch-shipping parts are necessarily located.

With this particular object in view the 25 present improvements will be fully understood from the following description, in connection with the accompanying drawings, in which—

Figure 1 is a perspective view of so much 30 of a mowing-machine as is necessary to illustrate the present improvements. Fig. 2 is an enlarged perspective view of a detail of the foot-operated lever for engaging the counter-shaft in either of the positions to which it 35 may be shifted. Fig. 3 is an enlarged perspective view of a portion of the tongue of the machine, together with the pivoted bell-crank and its connections, and also showing the adjustable devices, by means of which 40 the position of the hand-lever is adjusted. Fig. 4 is a sectional detail of the counter-shaft and the immediate devices for moving it endwise to disengage the gearing between the same and the crank-shaft.

45 Referring to the views, the numeral 1 denotes the tongue of the machine, and 2 the bell-crank, which is pivoted at one of its angles upon a stud 3, projecting from the side of a bracket 4, that is secured to said tongue 50 by means of a bolt 5. The counterbalance-spring J is connected to said bell-crank, and a connecting-rod 6 is employed, through the

medium of which the bell-crank is operated from the foot-lever 7. The gag-lever M is connected to the bell-crank herein by means 55 of a chain 8, and the hand-lever is pivoted, so that the driver need not stoop to reach it, and is located forward of the foot-lever on the tongue, so that the driver reaches forward and pulls backward on it to lift the cutter-bar in opposition to the push on the foot-lever, whereby the concurrent use of the two levers is greatly facilitated. The position I have selected is on the bell-crank, and I thereby not only get the lever as much as possible 60 out of the way, but make it practically a part of the bell-crank itself, and I am enabled by this arrangement to provide for adjusting the lever to different angles with respect to the lever without altering the adjustment of any 70 of the other parts.

The connection or attachment of the hand-lever to the bell-crank is made by means of a circular boss 9, cast or otherwise formed on the outer side of the bell-crank a little in front 75 of the pivot on which the crank swings. In the center of this boss is an opening 12, through which the bolt 17 passes to clamp the lever to the bell-crank, and around the bolt-hole a series of radial teeth or serrations 11 80 are formed. The lever 13 is conveniently made separate from and bolted to its stock or butt 15, which is provided with a circular hub-like portion 14 at its end corresponding to the boss on the bell-crank. Centrally of 85 this hub there is an opening to receive the bolt 17, which clamps the lever to the bell-crank, and around the opening on the inner face of the hub there are radial teeth or serrations 16, corresponding in shape, location, 90 and arrangement with those on the boss of the bell-crank. From this description and illustration the manner of securing the hand-lever to the bell-crank will be readily understood and its capability for various adjustments appreciated without further explanation. In Fig. 1 three adjustments of the lever are indicated, and of course it may be set in any intermediate position, all that is necessary being to loosen the bolt 17 sufficiently 100 for the teeth 11 and 16 to slip past one another and without detaching the lever from the bell-crank set it at any desired angle, after which the bolt is tightened up again and the

lever held as tightly as though actually integral with the bell-crank by the interlocking of the two sets of radial serrations.

In the operation of the machine the bell-crank is constantly vibrating, and of course the hand-lever must move with it. If the lever were located at the pivot of the bell-crank and adjustable around it, its upper end would vibrate back and forth in a nearly horizontal plane in front of the driver; but by attaching the lever to the bell-crank eccentrically to and in front of its axis it has a bodily up-and-down movement, with very little fore-and-aft swing.

The arrangement which I have devised for making the clutching mechanism of my patent of February 4, 1896, operable by the foot is as follows: The counter-shaft 20, the gearing 30 and 31, and the cam-groove 28 in the shaft-box 21 are the same as in the patent, as are also the pin 29 on the shaft, the catch 25 on the lever 22, and the stops or shoulders 26 and 27, against which the catch 25 engages when the lever 22 is in one or the other of its positions. So, also, is the lever herein, when considered generically, the same as that of the patent and has the same pivoted connection 23 with the shaft and the same spring 24 to keep the catch 25 normally engaged with the stops or shoulders. The patented lever, however, is required to be operated by hand, and the present improvement in this respect consists in the particular construction of the lever whereby I adapt it to be operated entirely by the foot of the driver when in his seat. To this end I provide the lower end of the lever with an extension 40, which projects rearwardly and downwardly from the pivoted portion, and at the extreme end of the extension it has a laterally-projecting footpiece 41, which extends parallel with the counter-shaft and at a right angle to the pivot of the lever to a point grassward beyond the pivot. When the gears 30 and 31 are in mesh, the lever 22 and its foot 41 stand in the position shown in Fig. 1 and in full lines in Fig. 2. In order to throw the parts out of gear, the driver has only to press his foot on the extension 41. The first effect of this action is to swing the lever lat-

erally on its pivot 23 until the catch 25 is released from the shoulder 26, and further pressure on the footpiece has the effect of rocking the shaft 20 and causing its pin 29 to move around in the spiral cam-groove 28, which shifts the shaft longitudinally grassward and moves the wheel 30 out of gear with the pinion 31. When the driver desires to throw the parts into gear again, he has only to hook his toe under the lever 22, (for which purpose it is conveniently formed with a knob 45,) press it slightly outward to disengage the catch 25 from the shoulder 27, and then push or throw it over toward the front with his foot. The positions and movements of the lever are clearly indicated in dotted lines in Fig. 2, from which the action will be readily understood when read in connection with the above description.

What I claim, and desire to secure, is—

1. In a mower, the combination of an end-wise-moving shaft, a lever pivoted at right angles thereon for rocking the same, a spring reacting between the lever and the shaft and holding said lever normally locked in engagement with a fixed stop or shoulder, and an angular footpiece projecting parallel with the shaft from an arm of the lever and extending on the other side of its pivot from said stop, whereby a single movement unlocks the lever and shifts its position.

2. In a mower, the combination of the counter-shaft 20, its bearing 21, the stop-shoulders 26, 27, the pin 29 projecting from the shaft and the cam-groove 28 in which said pin works, the lever 22 pivoted transversely on said shaft 20 and provided with the catch 25 on one side of its pivot, the arm 40, and the footpiece 41 extending from the arm on the other side of the lever's pivot, and the spring 24 reacting between the shaft and the lever and holding the catch normally engaged with either of the stops or shoulders on the bearing 21.

In testimony whereof I affix my signature in presence of two witnesses.

JOHN F. STEWARD.
